FLOWER HOLDER FOR USE ON TOMBSTONES

Oval P. Lairson, Rte. 1, P.O. Box 110,
Noble, Okla. 73068

Filed July 11, 1969, Ser. No. 18,175

Term of patent 14 years

Int. Cl. D31

U.S. Cl. D35—1

FIG. 1 is an elevational view of the flower holder for use on tombstones looking at one side thereof.

FIG. 2 is an elevational view of the opposite side of the holder.

FIG. 3 is a top view of the holder.

FIG. 4 is a bottom view of the holder.

FIG. 5 is an elevational view taken at one end of the holder.

FIG. 6 is an elevational view taken at the opposite end of the holder.

I claim:

The ornamental design for a flower holder for use on tombstones, substantially as shown.
